PROCESS FOR THE TREATMENT OF
HYDROCARBON OIL

Percival C. Keith, Jr., Peapack, N. J., assignor to
Gasoline Products Company, Inc., Newark,
N. J., a corporation of Delaware

Application November 16, 1933, Serial No. 698,253

4 Claims. (Cl. 196—48)

This invention relates to processes for the treatment of hydrocarbon oil, and pertains particularly to processes for producing gasoline and intermediate products by cracking crude petroleum, or other relatively heavy charging stock.

It is an object of my invention to provide a process for separating a charging oil such as crude petroleum, reduced crude, or even lighter oil, into lighter fractions and relatively heavy residue, separately cracking certain of the lighter fractions, and the residue, combining the cracked products, separating the combined cracked products into vapors and a residue, removing and condensing certain relatively light vapors as a desired product, condensing and recycling for further cracking certain intermediate vapor fractions and extracting from the residue and recycling for further cracking, certain of the lighter constituents thereof.

Another object is to provide an improved method and means for preheating at a constant rate, charging stock for a cracking process, by indirect heat exchange thereof with hot products from the process, which after being cooled by the heat exchange step, are used at a variable rate in other steps of the process.

The above mentioned and other objects and advantages of my invention, and the manner of attaining them, will be made clear in the following description and accompanying drawing.

The single figure of the drawing represents diagrammatically an oil cracking system embodying my invention. Referring more particularly to the drawing, reference numeral 1 indicates a charging line through which fresh, relatively heavy hydrocarbon oil is introduced, by means of pump 2. This oil, which may be crude petroleum, reduced crude or even lighter oil, either virgin or cracked, passes through heat exchangers 3 and 4 into evaporator or stripper 5, preferably through line 6 having valve 7, or alternatively through line 8 having valve 9 or through both lines simultaneously. Through line 6 the fresh oil is discharged over baffle plates, or similar contacting means, 10, while through line 8 the discharge is directed into the trap-out tray 11. The flow may be divided between pipes 6 and 8 to maintain the desired temperature condition in the evaporator. In this evaporator the fresh oil, which may enter at a temperature of about 625° F., is subjected to further heating by contact with rising hot vapors, and resulting vaporized portions of the oil rise through the tower 5, past baffle plates 10 and bubble plates or other fractionating devices 12, with attendant partial

condensation. The uncondensed vapors pass off through vapor line 13 into fractionator 14 and the condensate formed in evaporator 5 is collected on trap-out tray 11 along with unvaporized portions of the fresh charge.

The mixture of condensate and unvaporized charging stock, free from lighter fractions, is withdrawn from trap-out tray 11 through pipe 15, and is forced by pump 16 through heating coils 17 of combination furnace 18. The heated oil emerges from the furnace at a temperature which may vary considerably but which is sufficient to insure moderate cracking of the oil passing through the heating coils, for example sufficient to form from 8 to 12% of products in the gasoline boiling range per pass, preferably about 10%, this cracking being of a viscosity breaking nature. The temperature may range, for example, from 800° to 975° F., but preferably is about 860° F. Even higher temperatures may be used with charging stocks which have little tendency to form coke. The pressure used is preferably of moderate value, e. g. 250 pounds per square inch, but higher or lower pressures may be selected. The pressure may range from 50 pounds per square inch, to 850 pounds per square inch for example, or even higher, depending on the stock being cracked, but I prefer the lower pressures of the order of 200 or 300 pounds, in most cases. The resulting highly heated cracked products are then introduced through pipe 19 into the lower part of evaporator 5, which may be held at the same pressure as the outlet of the heater coil, or at a somewhat lower pressure of, for example, about 220 pounds per square inch. Valve 20 is furnished to provide any desired pressure drop. The point of introduction of the cracked products is preferably below the level of the liquid in the lower part of the evaporator, but in any event is below trap-out tray 11. Baffle plates or similar devices 21 are provided to prevent entrainment of heavy liquids in the vapors passing upwardly through the tower to a point above the trap-out tray.

Cracked residue or tar is withdrawn from the chamber 5 through line 22 having reducing valve 23, into the lower portion of a flash drum 24. This drum is equipped with a trap-out tray 25, located above the point of entrance of the residue, and a series of baffle plates 27 and bubble trays or other fractionating elements 28, which serve partially to fractionate the vapors rising in the flash drum. The pressure maintained in the drum 24 is preferably materially lower than that maintained in the evaporator 5, being for example,

about 5 pounds per square inch, although higher or lower pressures may be used. As a result of the reduction in pressure the lighter constituents of the introduced residue are vaporized and pass upwardly through the drum past the trap-out tray 25, being subjected to partial condensation by contact with the baffle plates and fractionating elements 27 and 28, which are supplied with reflux from an external source, through pipe 31, in the usual manner. Light fractionated vapors pass off from the top of the tower through vapor line 32, heat exchanger 33 and cooler 34, into flash distillate receiver 35. A portion of this flash distillate may be removed through pipe 36 and forced by pump 37 through line 38, both into the pipe 31 and through a branch line 39 into conduit 22 which conducts the unvaporized residue to the flash drum. The liquid so introduced into the line 22 serves to cool the products entering the lower part of the flash drum, thereby diminishing any tendency toward coke formation, either in the valves 23 and 30, or in the drum itself, and the liquid introduced through the line 31 serves as the cooling or refluxing medium for the upper portion of the tower 24.

The condensate collected on trap-out tray 25, being substantially free from extremely heavy products which tend very easily to form coke deposits under heat treatment, is removed through line 40 and forced by pump 41 into charging line 1 in mixture with the fresh charge, for further heat treatment in connection therewith. The portions of this condensate which are sufficiently low in boiling point are vaporized in the vaporizer 5 and carried off through vapor line 13 to fractionator 14. The portions of this condensate which are too heavy to be vaporized are collected on the trap-out tray 11 and withdrawn through pipe 15 for further conversion in the viscosity breaker heating coil 17. The vapors entering the fractionator 14 through line 13 are subjected to fractionation by the action of baffle plates 42 and bubble trays or other fractionating elements 43, with the resulting formation of a reflux condensate, a portion of which is collected on a trap-out tray 44, and the remainder of which collects in the bottom of the tower.

The condensate collected in the trap-out tray 44 is withdrawn through pipe 45 and passed under pressure generated by pump 46, which is preferably adapted to cause a substantially constant flow of oil, in a divided path both through line 47 and heat exchanger 48, and line 49 and heat exchangers 4, the division of flow being controlled by valves 51 and 52. The two lines mentioned join at point 53 and from that point condensate is passed through line 54, having branch line 55 and 56, into the tower 5, pipe 55 entering at a point above the baffle plates 21, and pipe 56 entering above the bubble trays 12, these two lines providing reflux medium for the operation of the tower. Line 57 is provided for introducing a portion of the condensate as a refluxing medium over the baffle plates 42 in the lower portion of tower 14. Valves 58, 59, and 60 provide the necessary control.

It is desired that the quantity of reflux condensate passing in heat exchange relation with the fresh charge, by agency of heat exchangers 4 shall be substantially constant whereby substantially constant preheating of the fresh charge may be assured. In order to maintain this flow of condensate substantially unvaried, a flow controller 61 is placed in the line 49 between heat exchangers 4 and its junction with line 47 at

point 53, and this flow controller is arranged to operate a valve 62 in a return line 63, which is connected to the fractionator 14, for example at trap-out tray 44, and serves as a by-pass for the cooled condensate. When a change tends to occur in the quantity of condensate traveling through heat exchangers 4, for any reason, for example, as a result of adjustment of valves 58, 59 or 60 the flow controller 61 causes a compensating adjustment of valve 62, which will divert a greater or lesser amount of the condensate back to the fractionator 14, thereby maintaining the flow thereon, through the heat exchangers 4, substantially constant. Thus if valve 58 is opened from a given position, by-pass valve 62 is automatically closed somewhat to compensate. It is also desired that the temperature in the base of the stabilizer tower 80 be maintained substantially constant, and to insure this result by-pass line 50, having valve 50', is provided. The hot oil flowing through line 47 is diverted through by-pass 50 automatically by opening or closing of valve 50' under control of temperature responsive device 48' located in circulating line 84, or otherwise adapted to determine the temperature in the base of the stabilizer tower. Any change in the flow of oil through line 49, which might tend to occur as a result of a change in the setting of valve 51 or valve 50', is also compensated for by the automatic adjustment of by-pass valve 62. By this arrangement of controllers all or part of the reflux condensate withdrawn from tower 14 through pipe 45, may be passed through pipes 55, 56 and 57 as a refluxing medium, without altering the rate of heat transfer in exchangers 4 and 48.

A light condensate may be removed through pipe 66, from trap-out tray 65, located near the top of the fractionator, and be forced by pump 67 through heat exchangers 3 and adjustable auxiliary cooler 69 back into the top of the fractionator as a refluxing medium. The quantity of reflux so returned is adjusted by automatic regulation of valve 68 under control of temperature responsive device 68' in vapor line 70, to give the desired boiling characteristics to the light vapors passing off from the top of the fractionator. These vapors are those falling in the desired boiling range, e. g. gasoline, that the end point of the distillate formed being that desired for the final product.

These vapors pass off from the top of the fractionator through vapor line 70 and condenser 71 through line 72, having reducing valve 73, into the primary gas separator 74. The fractionator 14 may be held under substantially the same pressure as that of the evaporator 5, or a slightly lower pressure, e. g. 220 pounds per square inch, and the primary gas separator 74 may likewise be held under substantially the same pressure as that of the fractionator 14, or a somewhat lower pressure. In the primary gas separator fixed gases and very light vapors, mainly those lying outside of the desired gasoline boiling range, are separated and pass off through partial condenser 65 or fractionator 75, and vapor line 76, while the liquid condensate collecting in separator 74 is removed through draw-off line 77, and forced by pump 78 through heat exchanger 79 and auxiliary heater 79' into an intermediate point in the stabilizer tower 80, which is preferably held at a higher pressure than that of the fractionator 14, for example, about 400 pounds per square inch, although higher or lower pressure may be used. The reference numeral 81' indicates a refluxing

line through which a cool refluxing medium may be introduced into the top of the stabilizing column in the usual manner. The stabilized gasoline is withdrawn from the bottom of the stabilizer 80 through line 81, and passed through heat exchanger 79 and cooler 82, into receiver 83. A quantity of the stabilized gasoline is preferably removed from the bottom of the stabilizer through line 84, circulated by pump 85 through heat exchanger 48, and returned to the stabilizer at a higher temperature to supply added heat for aiding the stabilization process.

By means of the heat exchanger 79 the gasoline to be stabilized in the stabilizer 80 is first pre-heated by indirect heat exchange with the finished stabilized gasoline withdrawn from the bottom of the tower. The heat exchanger 48 on the other hand, provides means whereby additional heat necessary for reboiling may be supplied to the base of the stabilizer, this heat being derived from reflux condensate withdrawn from fractionator 14. This reflux is at the same time cooled, so that it will have the desired temperature for introduction as reflux into the evaporator 5 and fractionator 14.

Reflux condensate collecting in the base of fractionator 14 is withdrawn through line 86 and forced by pump 87 through vapor phase heating coils 88 of furnace 18. The highly heated cracked products pass from the furnace through line 89 at a relatively high cracking temperature into the lower part of evaporator 5, preferably below the liquid level therein. The temperature of the cracked products leaving heating coil 88 may vary considerably depending on such factors as the character of the charging stock and character of the desired products, as well as the applied pressure and time of heating contact. It may, for example, vary over a range of from 875° to 1200° F. but suitably is from 900° to 1000° F., preferably about 950° F. The pressure of the products leaving the vapor phase heating coil 88 may be from a few pounds to several hundred pounds higher in value than the pressure maintained in evaporators 5, preferably, however, the pressure is about 750 pounds per square inch, gauge. The necessary reduction in pressure of the vapor phase cracked products prior to their entrance into evaporator 5, is effected by a pressure reducing valve 90, located in the line 89. The time of passage of the clean condensate through the heating coil 88 is preferably so selected that a relatively large amount of cracking of the products in the gasoline boiling range, per pass, is effected. The cracking per pass may be, for example, from 15 to 25%, preferably about 20%, although the percentage permissible will necessarily vary with different charging stocks, the cleaner the stock the higher the cracking percentage possible.

The highly heated cracked products entering the base of evaporator 5 through line 89 aid in separating into vapors and liquid residue, the cracked heavy oil introduced through line 19, the highly heated vapors passing upwardly through the evaporator and aiding in heating the fresh charge and reflux condensate from tower 24 introduced through line 6, and stripping the lighter fractions therefrom.

The heavy flashed residue or tar remaining in liquid form in the base of flash drum 24 is withdrawn through draw-off pipe 91 and is forced by pump 92 through cooling coil 93 into receiver 94. A portion of the cooled tar is diverted through by-pass pipe 95 having control valve 96, into the pipe 91, just at the point where

it leaves the flash drum 24. This recirculated cooled tar serves to prevent the deposition of carbonaceous materials or other heavy products in the pipe 91, both by cooling the tar immediately upon its removal from the flash drum, and by increasing the velocity thereof through the pipe 91 above that which would obtain if this material were not recirculated.

While I have shown the two heating coils 17 and 18 as located in a single furnace having independent combustion chambers for portions of the two coils, and a common convection section for other portions of the two coils, a separate furnace may be used for each of the heating coils, such an arrangement lending slightly greater flexibility to the system.

In operation fresh charging stock of a relatively heavy nature, such for example, as a Mexican crude oil, reduced crude, or the like, is introduced into the unit through pipe 1, and passes through the heat exchangers 3 and 4, wherein the temperature thereof is raised by indirect heat exchange with condensate withdrawn from the fractionator 14, the temperature attained by the charging oil being, for example, about 625° F. more or less, and the heated oil is introduced into the evaporator 5, either at a point above the baffle plates 10, or at a point adjacent the trap-out tray 11, or both. The introduced oil is heated in the evaporator to a somewhat higher temperature by the hot vapors rising from the bottom of the evaporator, and as a result lighter portions of the fresh charging stock separate as vapors from the heavier portions which remain in liquid form and are collected on the trap-out tray 11. The vapors are subjected to partial condensation in the upper portion of the evaporator 5, and those remaining uncondensed pass off from the top thereof through vapor line 13, into the fractionator 14, the boiling characteristics of these vapors being regulated by the cooled refluxing liquid introduced through pipe 56. The unvaporized portions of the fresh charge, commingled with condensed portions of the vapors rising through the evaporator 5, are removed through line 15 and raised to a cracking temperature in the heated coil 17, this temperature being preferably about 860° F., more or less, although higher or lower temperature may be used, for example from 800° to 975° F., depending upon the character of the charging stock. This temperature and the cracking time should be great enough, however, to produce a moderate amount of cracking of the stock passing through the heater, the amount of cracked products in the gasoline boiling range formed per pass being as great as possible without deleterious deposition of coke in the heating coils and associated apparatus. The amount of conversion may be, for example, 8 to 12% per pass, preferably about 10%, this cracking step being in the nature of a viscosity breaking operation. The pressure at which the cracked products emerge from the heating coil 17 is preferably about 250 pounds per square inch, although higher or lower pressures may be used, ranging, for example, from 50 pounds per square inch upwards. The highly heated cracked products are then introduced into the base of evaporator 5 wherein they undergo separation into vapors and a liquid residue, the vapors rising through the tower against a downwardly flowing stream of reflux from pipe 55, and those remaining uncondensed serving to raise the temperature of the fresh charge introduced through line 75

6. The liquid residue remaining in the base of the evaporator is preferably withdrawn through line 22 and passed through reducing valve 23, into the base of flash drum 24, preferably maintained under a very low pressure, such as 5 pounds per square inch, wherein light products separate as vapors from a heavy liquid residue or tar. If desired part or all of this residue may be diverted from the process through line 101 and cooler 102, into receiver 103. The vapors released in flash drum 24 pass upwardly therethrough and are subjected to partial condensation by the action of contacting elements 27 and 28, which may be baffle plates and bubble trays respectively, and the downwardly flowing reflux liquid introduced through line 31. Condensate formed is collected on the trap-out tray 25 and this may have a temperature of, for example, about 630° F., although higher or lower temperature may be used. This condensate is passed through the line 40 into the charging line 1 where it mingles with the fresh stock and is recycled through the system. Any portion of the condensate from the line 40 which is not vaporized in the evaporator 5 is caught on trap-out tray 11 and recycled through the viscosity breaking heating coil 17. Those vapors which remain uncondensed at the top of the flash drum 24 pass off through line 32, heat exchanger 33, and cooler 34 into the flash distillate receiver 35. A portion of the flash distillate collected therein may be forced through pipes 36 and 38 into the top of the flash drum 24 as reflux, and another portion may be diverted through line 39 into the line 22 to commingle with the hot residue therein and prevent coking of the valves 23 and 30, and associated apparatus. In order that the level of the liquid in receiver 35 shall not rise above a predetermined value, a portion of the flash distillate may be diverted through line 97 and heat exchanger 33 into line 47, where it is commingled with reflux withdrawn from fractionator 14, and subsequently treated in a manner which will be described more fully hereinafter. The level of liquid in the receiver 35 may be automatically controlled by a float mechanism 98 which is connected with valve 99 and serves to open that valve upon a predetermined rise of liquid in the flash drum 35, thereby diverting an additional amount thereof through line 97. The tar accumulating in the base of flash drum 24 may be withdrawn through draw-off line 91 and cooler 93 into receiver 94. During the drawing off of the tar a quantity of the cooled tar may be recirculated through line 95 and the pipe 91, just at the point where it leaves the drum 24, this circulating liquid serving to increase the fluid velocity through the pipe 91, while at the same time cooling the tar therein and in this manner preventing the deposition of heavy materials in that line. Reference numeral 104 indicates a relief valve set to open when excessive pressure is exerted in drum 24.

65 The vapors removed from the top of evaporator 5, which for example, may have a temperature of about 750° F. and a pressure of 220 pounds per square inch, are introduced into the fractionator 14 through line 13 having a valve 13' therein. The pressure in the fractionator is preferably approximately the same as that in the evaporator 5, or slightly lower, for example 220 pounds per square inch, any necessary adjustment thereof being made by means of valve 13'. In the fractionator 14 the introduced vapors undergo fractionation in the usual manner,

5 with the resulting formation of reflux condensate, a portion of which collects on trap-out tray 44, and another portion of which collects in the base of the fractionator 14. The condensate collected on tray 44 is removed through pipe 45 and forced through lines 47 and 49 which join at point 53. The line 47 has heat exchanger 48 therein, by means of which the reflux condensate is brought into indirect heat exchange relation with gasoline removed from and returned to stabilizer column 80, thereby serving to heat the gasoline and maintain the desired temperature in the stabilizer tower. Line 49, on the other hand, is provided with heat exchangers 4, by means of which heat is extracted from the reflux condensate and transferred to the fresh charge passing through line 1. The commingled streams of condensate from lines 47 and 49, including any flash distillate from line 97 pass from point 53 through lines 55 and 56 to a point 10 below and a point above the trap-out tray 11 in evaporator 5. The quantity of oil passing through the several lines is regulated by valves 59 and 58, respectively, to give the desired refluxing action in the fractionator and evaporator, and the surplus is returned to an intermediate point in the fractionator column 14, for example the trap-out tray 44 from which it was withdrawn. The constancy of flow of reflux condensate through heat exchangers 4, and therefore uniformity of heating of the fresh charge, is insured by means of the flow controller 61, which adjusts by-pass or control valve 62 in such manner as to maintain constant the flow of reflux condensate through the heat exchangers 4, any excess of reflux condensate over that necessary for refluxing in fractionator 14 and evaporator 5 being returned through line 63 to the fractionator 14. Condensate collecting in the base of fractionator 14 is withdrawn 30 through line 86 and passed through vapor phase heating coils 88, wherein it is raised to a cracking temperature of, for example, about 950° F., and is held at a cracking temperature for a sufficiently long time to insure a moderate amount 35 of cracking. While the temperature to which the oil is raised may vary considerably, for example, from 875° to 1200° F., the temperature is most desirably kept within the range of 900° to 1000° F., preferably about 950° F., and the 40 time of contact is adjusted to produce a cracking per pass of about 15 to 25%, preferably about 20%, per pass. The pressure maintained on the oil while undergoing cracking in the heating coil 88, may range from a few pounds per square inch above the pressure held in the evaporator 5, upward, but is preferably about 750 pounds per square inch gauge. The highly heated cracked products are then reduced in pressure by action of reducing valve 90 and introduced into the base of the evaporator 5, preferably below the level of the liquid residue therein, and aid in reboiling that residue, resulting 45 vapors rising through the column and contacting with the fresh charge at a point above the trap-out tray 11. The reflux liquid introduced through line 55 and the baffle plates or other contacting means 21 serve to prevent entrained particles of heavy residue from rising with these vapors to a point above the trap-out tray. 50

55 In fractionator 14 the rising vapors adjacent the top of the column are refluxed by light condensate removed from trap-out tray 65, cooled in heat exchangers 3 by indirect contact with fresh charge and, if desired, further cooled in auxili- 55

iary water cooler 69. The cooled condensate is then introduced in desired quantities into the top of the fractionator tower, the cool light condensate so returned serving to control the boiling characteristics of the vapors leaving the fractionator, to give the desired gasoline distillate. These vapors are condensed in condenser 71 and are then introduced into the gas separator 74, either with or without a reduction in pressure thereof. In the separator 74 the fixed gases and very light vapors which have not been condensed in passage through condenser 71, pass off as vapors through the partial fractionating column 75 and pipe 76 to an absorber column or any other desired destination. The incompletely stabilized distillate is removed from separator 74 and passed through line 77, at an increased pressure generated by pump 78, through heat exchanger 79 into an intermediate point in stabilizer column 80, wherein it undergoes stabilization in the usual manner, the stabilized gasoline being removed through draw-off line 81 and heat exchanger 79 wherein it gives up contained heat to the distillate being introduced into the stabilizing column, 25 and is collected in the receiver 83 after cooling in cooler 82. Any fixed gases and extremely light hydrocarbon vapors pass off from the top of the stabilizer column through line 100 in the usual manner. A portion of the distillate from separator 74 may be diverted through pipe 77' and cooler 78' into the top of the fractionator column 14 as a refluxing medium in the usual manner, control being effected by valve 179.

While I have described a particular embodiment of my invention for the purpose of illustration, it should be understood that various modifications and adaptations thereof, occurring to one skilled in the art, may be made within the spirit of the invention as set forth in the appended 40 claims.

I claim:

1. The process of treating hydrocarbon oil which comprises heating fresh relatively heavy hydrocarbon oil to a cracking temperature under 45 superatmospheric pressure, to cause cracking thereof, introducing the resulting cracked products into a vaporizing zone wherein vapors separate from a liquid residue, removing said vapors and introducing them into a fractionating zone 50 wherein heavier fractions are separated as condensate from lighter fractions as vapors, remov-

ing hot condensate from said fractionating zone and passing the removed condensate, while still hot, in indirect heat exchange relation with said fresh oil, to preheat said fresh oil, dividing said removed condensate, after the heat exchange 5 step, into two streams, introducing one stream into said vaporizing zone as a refluxing medium, returning the other stream into said fractionating zone, varying the quantity of oil passing through said one stream to give the desired refluxing effect in the vaporizing zone, and varying said other stream to regulate the amount of preheating of said fresh oil.

2. A process according to claim 1 wherein upon variation of said one stream to produce a desired 15 refluxing effect, said other stream is correspondingly varied to maintain substantially constant the flow of condensate in indirect heat exchange with said fresh oil.

3. A process according to claim 1 wherein added oil is injected into said two streams at the point of junction thereof and wherein upon variation of said one stream to produce a desired refluxing effect, said other stream is correspondingly varied to maintain substantially constant 20 the flow of condensate in indirect heat exchange with said fresh oil.

4. In the treatment of hydrocarbon oils in which the oil is subjected to cracking conditions, resultant products of cracking subjected to vaporization in a vaporizing zone and separated vapors subjected to fractionation in a fractionating zone, the method of preheating charging stock to the system and controlling refluxing 30 therein which comprises withdrawing hot condensate from the fractionating zone and cycling said condensate in a closed circuit by passing the withdrawn condensate in indirect heat exchange with fresh charging stock for the system to thereby preheat such charging stock, dividing the resultant cooled condensate after the heat exchange 35 step into two streams, conducting one stream to said vaporizing zone as a refluxing medium, conducting the other stream to said fractionating zone as a refluxing medium, varying the quantity 40 of oil passing through said one stream to give the desired refluxing effect in the vaporizing chamber and varying said other stream to regulate the amount of preheating of said fresh charging 45 stock.

PERCIVAL C. KEITH, JR.
